SUPPORT FOR BOWLING ALLEY MASKING UNITS

Robert I. Anderson, Grand Haven, and Bert Hoeker, Muskegon, Mich., assignors to The Brunswick-Balke-Collender Company, Chicago, Ill., a corporation of Delaware

Application March 12, 1947, Serial No. 734,100

5 Claims. (Cl. 273—54)

1

This invention relates to a support for a masking unit adaptable for use in conjunction with bowling alleys wherein a masking unit is located at the rear or pin end of the alley. The masking unit is positioned with its bottom immediately above the tops of the pins and serves to mask the wall and other structures behind the unit. The masking unit is rotatably supported so that it may be turned from a vertical toward a horizontal position when access is desired to the portion of the alley beneath the unit.

One object of the invention is to provide a new and improved support for one or more of the masking units.

Another object of the invention is to provide an improved support for a masking unit that is quite simple in construction and that may be easily adjusted so that the masking unit will be supported in any desired position, preferably in a vertical position.

A further object of the invention is to provide adjustable stop means against which the masking unit rests by gravity.

Other objects and advantages of the invention will appear from the following description taken in connection with the drawings, in which:

Fig. 1 is a plan view of a pair of masking units constituting a unitary assembly and the support for the masking units wherein each unit is supported independently of the other.

Fig. 2 is a front elevation of the masking units and the support shown in Fig. 1.

Fig. 3 is a side elevation of a masking unit and the support therefor.

Fig. 4 is an enlarged side elevation of the top portion of the support for a masking unit.

Fig. 5 is a plan view of the hinge of a hinged bracing member used in the support.

Fig. 6 is an elevation of the bracing member shown in Fig. 5 with portions broken away.

Fig. 7 is a plan view of a stop member against which the masking unit rests.

Fig. 8 is a side elevation of the stop member of Fig. 7.

While there is shown in the drawings and described in detail herein a structure embodying this invention, it is to be understood that the same is not limited to the specific form or application disclosed, and that it is the intention to cover all modifications and alternative constructions falling within the scope of the invention as expressed in the claims.

As shown in Figs. 1 and 2, an adjacent pair of bowling alleys 10 are provided with masking units 11 with one masking unit being above each alley.

2

Between the two alleys, as shown in Fig. 2, there is provided a raised portion 12 at the rear of the alleys, and the opposite sides of the pair of alleys are provided with ball return gutters 13 having their rear ends raised to substantially the same height as the raised portion 12. On either side of each alley 10 there are located ball gutters 14. Each masking unit 11 has a decorative front surface and is provided with an electric lamp 15 and a reflector structure 16 so that light may be directed down upon the pins. In the embodiment shown, the central portion 17 of each masking unit is solid while the space on either side thereof is provided with substantially parallel sloped slats 18 so spaced that a pin-boy behind the masking unit can look between the slats and see when a ball is coming. The remainder of the masking unit is made solid.

Each masking unit is rotatably supported on a substantially horizontal pipe 19 located behind the masking units and above their centers of gravity. The masking units are provided with rear plates 20 having holes therein engaging the pipe 19 so that each masking unit will be rotatably supported on the pipe. Each masking unit is provided with two of these plates, with each plate being positioned near an edge of the masking unit.

The horizontal pipe 19 is supported by spaced post members or support pipes 21 with the bottom end of each support pipe being rotatably mounted on the side of the raised portion 12 or the side of the raised portion of the ball return gutter 13. The upper end of the support pipe 21 extends to a point adjacent the horizontal pipe 19. This upper end is provided with a telescoped auxiliary pipe 22 attached to the top end of the support pipe 21 as by welding 23. The upper end of the auxiliary pipe 22 is provided with a yoke assembly 24 adapted to be held around the horizontal pipe 19 and clamped thereto by a pair of bolts 25. That portion of the yoke assembly 24 that extends around the pipe 19 is preferably provided with a rubber liner 26. The support pipe 21 is sloped from its bottom end toward the masking units 11 and as it has its bottom end rotatably attached to a base and its upper end rotatably attached to the pipe 19 it may be adjusted so as to vary its angle with the horizontal.

The support pipe 21 is braced by a bracing pipe 27 having its rear end rotatably attached to the same base to which the support pipe 21 is attached and located to the rear of the support pipe. The bracing pipe is sloped at a greater angle than the support pipe 21 and extends to a

point adjacent the support pipe. The top portion of the bracing pipe 27 is provided with a sleeve 28 around the support pipe 21 with the sleeve being connected by a hinge 29 to the remainder of the bracing pipe 27. The sleeve 28 is provided with a set screw 30 by means of which it may be tightly clamped to the support pipe 21.

Immediately below the top end of the bracing pipe 27 there is located a stop member 31 comprising a sleeve 32 slidably mounted on the support pipe 21, a pipe 33 extending toward the bottom of the masking unit 11 and a cross-pipe 34 attached to the free end of the pipe 33 and against which the bottom of the masking unit 11 rests. The cross-pipe 34 is arranged in substantially horizontal position. The sleeve 32 is provided with a set screw 35 so that the sleeve may be locked on the support pipe 21.

The support pipe 21, auxiliary pipe 22, bracing pipe 27, and stop member pipe 33 are preferably arranged so that their axes lie substantially in a single vertical plane. They are so arranged that the masking unit 11 will bear against the stop member pipe 34 and be held in a substantially vertical position. In order to achieve this vertical arrangement, the slope of the support pipe 21 may be adjusted by loosening the set screw 30 on the bracing pipe sleeve 28 and arranging the support pipe 21 in the particular angular relationship desired. This will also serve to locate the masking unit 11 in a desired position. The set screw 35 on the stop member 31 may be loosened and the stop member moved up or down the support pipe 21 so that the masking unit 11 hangs exactly vertical or at any other desired position. The height of the horizontal pipe 19, and thus the height of the masking unit, may be varied by adjusting the length of the auxiliary pipe 22 outside the support pipe 21. After this height has been determined, the auxiliary pipe 22 may be permanently attached to the support pipe 21 by welding 23.

Although the lamp 15 serves to direct light down on the bowling pins, additional light is often desired and this is provided by locating a lamp 36 behind the central solid portion 17 so that the light from this lamp is directed above the central portion 17. This serves to illuminate the top of the decorated masking unit as the central portion 17 is located in front of the main body of the masking unit, as shown in Figs. 1 and 3, and has its top portion open.

When access is desired to the portion of the bowling alley beneath the masking unit so that the alley may be polished or otherwise treated, the masking unit may be turned about the pipe 19 to the position shown in dotted lines in Fig. 3. The unit may be held in this position by means of a brace 37 or the like.

Each pair of alley masking units 11 is provided with one narrow unit 38 located above the ball return gutter 13. Each masking unit 11 is locked on the horizontal pipe 19 by a pair of lock rings 39 with each lock ring located against a support plate 20 and both rings preventing sliding movement of the plates 20 on the pipe 19.

We claim:

1. In combination with a bowling alley having a masking unit for the pin supporting end of the alley, a support for said masking unit comprising a substantially horizontal member, means for rotatably supporting the masking unit on said member at a point above the center of gravity of said unit, a base member below the horizontal member and at one side of the bowling alley, a

post member having its lower end rotatably attached to the base member and its upper end rotatably attached to the horizontal member, so that the angular relationship between the post member and the base member may be varied to vary the location of the masking unit relative to the bowling alley, a bracing member extending between the post member at a point intermediate its ends and the base member and slidably attached to the post member and rotatably attached to the base member on an axis of rotation that is substantially at right angles to the bracing member, said bracing member including two portions hingedly attached together on an axis substantially at right angles to the bracing member, and a stop member mounted on the post member and against which the lower portion of the masking unit rests to maintain the unit in substantially vertical position.

2. In combination with a bowling alley having a masking unit for the pin supporting end of the alley, a support for said masking unit comprising a substantially horizontal pipe, means for rotatably supporting the masking unit on said pipe at a point above the center of gravity of said unit, a base member below the horizontal pipe and masking unit and at one side of the bowling alley, a support pipe having its lower end rotatably attached to the base member and its upper end rotatably attached to the horizontal pipe, so that the angular relationship between the pipe and the base member may be varied to vary the location of the masking unit relative to the bowling alley, said support pipe being inclined from its bottom end toward the masking unit, a bracing pipe having one end rotatably attached to the base member and its upper end slidably attached to the support pipe so as to be rotatable in substantially the same plane as the support pipe, said bracing pipe being located on the side of the support pipe opposite the masking unit and including two portions hingedly attached together so as to be rotatable substantially in said plane, a stop member slidably mounted on the support pipe beneath the bracing pipe and against which the lower portion of the masking unit rests to maintain the unit in substantially vertical position, means for locking the bracing pipe on the support pipe, and means for locking the stop member on the support pipe.

3. In combination with a bowling alley having a masking unit for the pin supporting end of the alley, a support for said masking unit comprising a substantially horizontal pipe, means for rotatably supporting the masking unit on said pipe at a point above the center of gravity of said unit, a base member below the horizontal pipe and masking unit and at one side of the bowling alley, a support pipe having its lower end rotatably attached to the base member and its upper end rotatably attached to the horizontal pipe, so that the angular relationship between the support pipe and base member may be varied to vary the location of the masking unit relative to the bowling alley, said support pipe being inclined from its bottom end toward the masking unit, a bracing pipe having one end rotatably attached to the base member and its upper end slidably attached to the support pipe opposite the masking unit and including two portions hingedly attached together at a point adjacent the support pipe so as to be rotatable in substantially the same plane as said support pipe, a stop member slidably mounted on the support pipe beneath the bracing pipe and including a substantially horizontal out-

er portion against which the lower portion of the masking unit rests to maintain the unit in substantially vertical position, means for locking the bracing pipe on the support pipe, and means for locking the stop member on the support pipe.

4. In combination with a bowling alley having a masking unit for the pin supporting end of the alley, a support for said masking unit comprising a substantially horizontal pipe, means for rotatably supporting the masking unit on said pipe at a point above the center of gravity of said unit, a base member below the horizontal pipe and masking unit and at one side of the bowling alley, a support pipe having its lower end rotatably attached to the base member and its upper end extending to a point adjacent the horizontal pipe, an auxiliary pipe telescoped within said upper end and attached thereto with its outer end rotatably attached to the horizontal pipe, said rotatable connections being arranged to permit varying the angular relationship between the support pipe and base member, said support pipe being inclined from its bottom end toward the masking unit, a bracing pipe having one end rotatably attached to the base member and its upper end slidably attached to the support pipe, said bracing pipe being located on the side of the support pipe opposite the masking unit and including two portions hingedly attached together at a point adjacent the support pipe with said portions being movable in a substantially vertical plane about the hinge and on the base member, a stop member including a pipe slidably mounted on the support pipe beneath the bracing pipe and having a substantially horizontal pipe section on the outer end of the stop member pipe against which the lower portion of the masking unit rests to maintain the unit in substantially vertical position, means for locking the bracing pipe on the support pipe, and means for locking the stop member pipe on the support pipe, said support pipe, auxiliary pipe, bracing pipe and stop member pipe having axes lying substantially in a single vertical plane.

5. In a bowling alley assembly including a pair of alleys arranged adjacent and parallel to each other, a ball return gutter adjacent each edge of the assembly including a raised portion forming a base member at the pin end of the alleys, a similar raised portion forming a base member be-

tween the alleys and also at the pin end, and a masking unit above each alley at the pin end thereof, support means for the masking units comprising a substantially horizontal pipe located near the tops of said units and at the rear thereof, means for rotatably mounting each masking unit on said horizontal pipe, a support pipe for each of said base members having its lower end rotatably attached to its base members and its upper end extending to a point adjacent to but below the horizontal pipe, an auxiliary pipe telescoped within said upper end and attached thereto with its outer end rotatably attached to the horizontal pipe, said rotatable connections being arranged to permit varying the angular relationship between the support pipe and base member, said support pipe being inclined from its bottom end toward the masking unit, a bracing pipe having one end rotatably attached to said base member and its upper end slidably attached to the support pipe, said bracing pipe being located on the side of the support pipe opposite the masking unit and including two portions hingedly attached together at a point adjacent the support pipe with said portions being movable in a substantially vertical plane about the hinge and on the base member, a stop member including a pipe slidably mounted on a support pipe beneath the bracing pipe and having a substantially horizontal pipe section on the outer end of the stop member pipe against which the lower portion of the masking unit rests to maintain the unit in substantially vertical position, means for locking the bracing pipe on the support pipe, and means for locking the stop member pipe on the support pipe, said support pipe, auxiliary pipe, bracing pipe, and stop member pipe having axes lying substantially in a single vertical plane.
